US00D618632S

(12) **United States Design Patent**
Chang et al.

(10) **Patent No.:** US D618,632 S
(45) **Date of Patent:** ** Jun. 29, 2010

(54) **HEAT DISSIPATION DEVICE**

(75) Inventors: **Hsueh-Chen Chang**, Miao-Li Hsien (TW); **Shan-Ju Lin**, Miao-Li Hsien (TW)

(73) Assignee: **Foxsemicon Integrated Technology, Inc.**, Chu-Nan, Miao-Li Hsien (TW)

(**) Term: **14 Years**

(21) Appl. No.: **29/346,023**

(22) Filed: **Oct. 26, 2009**

(30) **Foreign Application Priority Data**

Jul. 21, 2009 (CN) 2009 3 0309755

(51) **LOC (9) Cl.** 13-03

(52) **U.S. Cl.** D13/179

(58) **Field of Classification Search** D13/179; 165/80.3, 104.33, 151, 122, 185; 257/706, 257/707, 718-722; 361/687, 695, 697, 700, 361/702, 704, 709, 710, 711, 719

CLAIM

The ornamental design for a heat dissipation device, as shown.

DESCRIPTION

FIG. 1 is a perspective view of a heat dissipation device showing our new design.

FIG. 2 is a front elevational view thereof.

FIG. 3 is a rear elevational view thereof.

FIG. 4 is a left-side, elevational view thereof.

FIG. 5 is a right-side, elevational view thereof.

FIG. 6 is a top plan view thereof; and,

FIG. 7 is a bottom plan view thereof.
